CLAIM

The ornamental design for a housing for telephone switchboard, as shown and described.

DESCRIPTION

FIG. 1 is a front elevational view of a housing for telephone switchboard showing my new design;
FIG. 2 is a top plan view thereof;
FIG. 3 is a bottom plan view thereof;
FIG. 4 is a rear elevational view thereof;
FIG. 5 is a right side elevational view thereof, the left side being a mirror image; and,
FIG. 6 is an enlarged cross-sectional view thereof taken on line 6—6 of FIG. 1.
